(57) **CLAIM**

The ornamental design for an electric motor with undulating membrane for watercraft, as shown and described.

DESCRIPTION

FIG. 1.1 is a front view of an electric motor with undulating membrane for watercraft:

FIG. 1.2 is a bottom view of the electric motor of FIG. 1.1; FIG. 1.3 is a front left side perspective view of the electric motor of FIG. 1.1;

FIG. 1.4 is a back view of the electric motor of FIG. 1.1; FIG. 1.5 is a front right side perspective view of the electric motor of FIG. 1.1;

FIG. 1.6 is a left side view of the electric motor of FIG. 1.1; FIG. 1.7 is a rear left side perspective view of the electric motor of FIG. 1.1;

FIG. 1.8 is a rear right side perspective view of the electric motor of FIG. 1.1;

FIG. 1.9 is a right side view of the electric motor of FIG. 1.1; and

FIG. 1.10 is a top view of the electric motor of FIG. 1.1.
